(57) **ABSTRACT**

A method of automatically sequencing an LED light string. The LED light string includes a plurality of LED modules. The method includes steps of: (a) building a start reference time before the LED modules start to operate, (b) generating a plurality of time difference values from the start reference time when a working voltage of each of the LED modules rises to an identification voltage after the LED modules operate, (c) determining the sequence of the LED modules according to the time difference values to achieve an automatic sequencing function.

LED LIGHT STRING WITH AUTOMATIC SEQUENCING FUNCTION AND METHOD OF AUTOMATICALLY SEQUENCING THE SAME

BACKGROUND

Technical Field

The present disclosure relates to an LED light string with automatic sequencing function and a method of automatically sequencing the same, and more particularly to an LED light string with automatic sequencing function and a method of automatically sequencing the same by calculating time difference values.

Description of Related Art

The statements in this section merely provide background information related to the present disclosure and do not necessarily constitute prior art.

Since light-emitting diode (LED) has the advantages of high luminous efficiency, low power consumption, long life span, fast response, high reliability, etc., LEDs have been widely used in lighting fixtures or decorative lighting, such as Christmas tree lighting, lighting effects of sport shoes, etc. by connecting light bars or light strings in series, parallel, or series-parallel.

Take the festive light for example. Basically, a complete LED lamp includes an LED light string having a plurality of LEDs and a drive unit for driving the LEDs. The drive unit is electrically connected to the LED light string, and controls the LEDs by a pixel control manner or a synchronous manner by providing the required power and the control signal having light data to the LEDs, thereby implementing various lighting output effects and changes of the LED lamp.

According to the present technology, in order to drive the LEDs of the LED light string to diversify light emission, the LEDs have different address sequence data. The LEDs receive light signals including light data and address data. If the address sequence data of the LEDs are the same as the address data of the light signals, the LEDs emit light according to the light data of the light signals. If the address sequence data of the LEDs are not the same as the address data of the light signals, the LEDs ignore the light data of the light signals.

At present, most of the LED sequence methods of the LED light string are complicated and/or difficult. For example, before the LEDs are combined into an LED light string, it is necessary to burn different address sequence data for each LED. Afterward, the LEDs are sequentially arranged and combined into the LED light string according to the address sequence data. If the LEDs are not arranged in sequence according to the address sequence data, the diversified light emission of the LEDs cannot be correctly achieved.

SUMMARY

An object of the present disclosure is to provide an LED light string with automatic sequencing function to solve the problem of the prior art using address to sequence LEDs of an LED light string.

In order to achieve the above-mentioned object, the LED light string with automatic sequencing function includes a circuit switch, a plurality of LED modules, and a control unit. The LED modules are electrically connected to the

circuit switch. Each LED module includes an identification circuit. The identification circuit is connected to a drive voltage source. The control unit generates a control signal to turn on and turn off the circuit switch. Before the LED modules start to operate, the control unit turns off the circuit switch so that a working voltage of each LED module is less than an identification voltage and the identification circuit builds a start reference time. The control unit turns on the circuit switch so that the working voltage increases to the identification voltage and the identification circuit generates a plurality of time difference values from the start reference time. The LED modules determine the sequence of the LED modules according to the time difference values to achieve an automatic sequencing function.

In one embodiment, the time difference values are compared with a plurality of time difference ranges to determine the sequence of the LED modules.

In one embodiment, the time difference ranges are built in a lookup table.

In one embodiment, the identification circuit includes a plurality of diodes, a switch, a resistor, and a switching switch. The diodes are connected in series. The switch is connected to the diodes in series to form a series-connected path. A first end of the resistor is connected to a first end of the series-connected path. The switching switch is connected to a second end of the series-connected path and a second end of the resistor, and switches the operation of the diodes and the switch of the series-connected path, or the operation of the resistor.

In one embodiment, the identification circuit includes a plurality of p-type MOSFET switches, a p-type MOSFET switch, and a switching switch. The p-type MOSFET switches are connected in series to form a series-connected path. A first end of the p-type MOSFET switch is connected to a first end of the series-connected path. The switching switch is connected to a second end of the series-connected path and a second end of the p-type MOSFET switch, and switches the operation of the p-type MOSFET switches of the series-connected path, or the operation of the p-type MOSFET switch.

In one embodiment, the identification circuit includes a plurality of n-type MOSFET switches, a n-type MOSFET switch, and a switching switch. The n-type MOSFET switches are connected in series to form a series-connected path. A first end of the n-type MOSFET switch is connected to a first end of the series-connected path. The switching switch is connected to a second end of the series-connected path and a second end of the n-type MOSFET switch, and switches the operation of the n-type MOSFET switches of the series-connected path, or the operation of the n-type MOSFET switch.

In one embodiment, the LED modules are connected in series to form the LED light string.

In one embodiment, the LED modules are connected in series and in parallel to form the LED light string.

In one embodiment, the LED modules are connected in parallel and in series to form the LED light string.

Accordingly, the LED light string with automatic sequencing function is provided to determine the sequence of the LED modules by using the built-in lookup table to acquire the relationship between the time difference values and the sequence of the LED modules, thereby simplifying the circuit design and quickly complete the sequence of the LED light string.

Another object of the present disclosure is to provide a method of automatically sequencing an LED light string to

solve the problem of the prior art using address to sequence LEDs of an LED light string.

In order to achieve the above-mentioned object, the LED light string includes a plurality of LED modules. The method includes steps of: (a) building a start reference time before the LED modules start to operate, (b) generating a plurality of time difference values from the start reference time when a working voltage of each of the LED modules rises to an identification voltage after the LED modules operate, (c) determining the sequence of the LED modules according to the time difference values to achieve an automatic sequencing function.

In one embodiment, the step (a) further includes a step of turning off a circuit switch electrically connected to the LED modules so that the working voltage of each of the LED modules is less than the identification voltage to building the start reference time.

In one embodiment, the step (b) further includes a step of turning on the circuit switch so that the working voltage rises to the identification voltage.

In one embodiment, the time difference values are compared with a plurality of time difference ranges to determine the sequence of the LED modules.

In one embodiment, the time difference ranges are built in a lookup table.

Accordingly, the method of automatically sequencing an LED light string is provided to determine the sequence of the LED modules by using the built-in lookup table to acquire the relationship between the time difference values and the sequence of the LED modules, thereby simplifying the circuit design and quickly complete the sequence of the LED light string.

It is to be understood that both the foregoing general description and the following detailed description are exemplary, and are intended to provide further explanation of the present disclosure as claimed. Other advantages and features of the present disclosure will be apparent from the following description, drawings and claims.

BRIEF DESCRIPTION OF DRAWINGS

The present disclosure can be more fully understood by reading the following detailed description of the embodiment, with reference made to the accompanying drawing as follows:

FIG. 1 is a block circuit diagram of an LED light string with automatic sequencing function composed of a plurality of LED modules connected in series according to the present disclosure.

FIG. 2 is a block circuit diagram of the LED light string with automatic sequencing function composed of the plurality of LED modules connected in series and in parallel according to the present disclosure.

FIG. 3 is a block circuit diagram of the LED light string with automatic sequencing function composed of the plurality of LED modules connected in parallel and in series according to the present disclosure.

FIG. 4A is a circuit diagram of an identification circuit of the LED module according to a first embodiment of the present disclosure.

FIG. 4B is a circuit diagram of the identification circuit of the LED module according to a second embodiment of the present disclosure.

FIG. 4C is a circuit diagram of the identification circuit of the LED module according to a third embodiment of the present disclosure.

FIG. 5 is a schematic waveform diagram of automatically sequencing the LED modules by calculating time difference values according to the present disclosure.

FIG. 6A is a circuit diagram of a parallel sequenced LED light string supplied power by a constant-voltage source according to a first embodiment of the present disclosure.

FIG. 6B is a circuit diagram of the parallel sequenced LED light string supplied power by a constant-current source according to the first embodiment of the present disclosure.

FIG. 7A is a circuit diagram of a parallel sequenced LED light string supplied power by the constant-voltage source according to a second embodiment of the present disclosure.

FIG. 7B is a circuit diagram of the parallel sequenced LED light string supplied power by the constant-current source according to the second embodiment of the present disclosure.

FIG. 8 is a flowchart of a method of automatically sequencing an LED light string according to the present disclosure.

DETAILED DESCRIPTION

Reference will now be made to the drawing figures to describe the present disclosure in detail. It will be understood that the drawing figures and exemplified embodiments of present disclosure are not limited to the details thereof.

Please refer to FIG. 1, which shows a block circuit diagram of an LED light string with automatic sequencing function composed of a plurality of LED modules connected in series according to the present disclosure. In this embodiment, the LED light string with automatic sequencing function (hereinafter referred to as the LED light string) includes a plurality of LED modules LED_1 ~ LED_N . The LED modules LED_1 ~ LED_N form a series-connected LED light string. A positive voltage end V_+ of the first LED module LED_1 is coupled to a DC positive voltage end V_{DC+} through a switch SLED. The LED modules in the middle are connected in series. A negative voltage end V_- of the last LED module LED_N is coupled to a DC negative voltage end V_{DC-} . Under this circuit structure, a control unit 100 is used to turn on and turn off the switch SLED, and then to control whether the DC driving voltage V_{DD} supplies power and drives the LED modules LED_1 ~ LED_N .

Please refer to FIG. 2, which shows a block circuit diagram of the LED light string with automatic sequencing function composed of the plurality of LED modules connected in series and in parallel according to the present disclosure. In this embodiment, the LED light string includes a plurality of LED modules LED_{11} ~ LED_{1N} , LED_{21} ~ LED_{2N} , LED_{M1} ~ LED_{MN} . The LED modules form a series-connected structure of N LED modules, and the LED light string is formed by connecting M series-connected structures in parallel. A positive voltage end V_+ of the first LED module LED_{11} , LED_{21} , LED_{M1} of the series-connected structures is coupled to a DC positive voltage end V_{DC+} through to a switch SLED. The LED modules in the middle are connected in series and/or in parallel. A negative voltage end V_- of the last LED module LED_{1N} , LED_{2N} , LED_{MN} is coupled to a DC negative voltage end V_{DC-} . Under this circuit structure, the control unit 100 is used to turn on and turn off the switch SLED, and then to control whether the DC driving voltage V_{DD} supplies power and drives the LED modules LED_{11} ~ LED_{1N} , LED_{21} ~ LED_{2N} , LED_{M1} ~ LED_{MN} .

Please refer to FIG. 3, which shows a block circuit diagram of the LED light string with automatic sequencing function composed of the plurality of LED modules con-

nected in parallel and in series according to the present disclosure. In this embodiment, the LED light string includes a plurality of LED modules LED_{11} - LED_{M1} , LED_{12} - LED_{M2} , LED_{1N} - LED_{MN} . The LED modules form a parallel-connected structure of M LED modules, and the LED light string is formed by connecting N parallel-connected structures in series. A positive voltage end V_+ of the first LED module LED_{11} , LED_{21} , LED_{M1} of the parallel-connected structures is coupled to a DC positive voltage end V_{DC+} through to a switch SLED. The LED modules in the middle are connected in series and/or in parallel. A negative voltage end V_- of the last LED module LED_{1N} , LED_{2N} , LED_{MN} is coupled to a DC negative voltage end V_{DC-} . Under this circuit structure, the control unit **100** is used to turn on and turn off the switch SLED, and then to control whether the DC driving voltage V_{DD} supplies power and drives the LED modules LED_{11} - LED_{M1} , LED_{12} - LED_{M2} , LED_{1N} - LED_{MN} .

Take the series-connected LED light string shown in FIG. 1 as an example, and it is assumed that the number of LED modules is 50. Each LED modules includes an identification circuit **10**. Please refer to FIG. 4A, which shows a circuit diagram of an identification circuit of the LED module according to a first embodiment of the present disclosure. In this embodiment, the identification circuit **10** includes, for example, but not limited to, three diodes D_{11} - D_{13} connected in series and a switch S_{11} connected to the series-connected diodes D_{11} - D_{13} . For example, the forward bias voltage of the three series-connected diodes D_{11} - D_{13} is 2.1 volts (each is 0.7 volts), plus the 0.7-volt forward bias voltage of the switch S_{11} is a total forward bias voltage of 2.8 volts. When the external DC driving voltage V_{DD} gradually increases and has not yet reached but is close to 2.8 volts (for example, but not limited to 2.6 volts), the switch SLED is turned off so that the DC driving voltage V_{DD} instantaneously decreases and is less than an identification voltage V_{IDEN} . At this condition, the switching switch SW is switched from the connection between a second end and a first end to the connection between the second end and a third end, that is, from a path composed of the series-connected diodes D_{11} - D_{13} and the switch S_{11} to a path composed of the resistor R_{11} . At this time, the time is recorded as the start reference time t_0 , and the start reference time t_0 is used as a reference time of calculating time difference values. When the voltages of the plurality of LED modules gradually increase to reach the identification voltage V_{IDEN} , the plurality of time difference values of the LED modules can be acquired. Take the first LED module as an example, a first time difference is $T_1 = t_1 - t_0$.

At this condition, the voltage waveforms of the positive voltage ends V_+ of all 50 LED modules relative to the negative voltage ends V_- (hereinafter referred to as the relative voltage waveforms) are as shown in FIG. 5. According to the circuit characteristics as shown in FIG. 5, that is, for different LED modules, the 50 sets of relative voltage waveforms have an obvious positive correlation with their series-connected sequence. Therefore, according to this circuit characteristic, the automatic sequence of all 50 LED modules can be achieved through the calculation of time difference values.

Specifically, since the relative voltage waveforms are the voltage characteristics of individual LED modules, all (50 sets) of relative voltage waveforms may be used to effectively determine the sequence of the corresponding LED modules, the concept of start reference (base) time is introduced. That is, by calculating the time difference between the time of each relative voltage waveform and the start

reference time, a plurality of different time difference values can be acquired. As shown in FIG. 5, since the DC driving voltage V_{DD} gradually increases and the voltage of the first LED module LED_1 reaches the identification voltage V_{IDEN} , a time difference value from the start reference time t_0 to the time when the voltage of the first LED module LED_1 reaches the identification voltage V_{IDEN} is the first time difference value T_1 . Similarly, since the DC driving voltage V_{DD} gradually increases and the voltage of the second LED module LED_2 reaches the identification voltage V_{IDEN} , a time difference value from the start reference time t_0 to the time when the voltage of the second LED module LED_2 reaches the identification voltage V_{IDEN} is the second time difference value T_2 . The rest may be deduced by analogy, since the DC driving voltage V_{DD} gradually increases and the voltage of the 50th LED module LED_{50} reaches the identification voltage V_{IDEN} , a time difference value from the start reference time t_0 to the time when the voltage of the 50th LED module LED_{50} reaches the identification voltage V_{IDEN} is the 50th time difference value T_{50} .

Before the start reference time t_0 , since the switch SLED is turned on, the DC driving voltage V_{DD} instantaneously increases, and all LED modules become a high potential state. At the start reference time t_0 , the switch SLED is turned off, and the DC driving voltage V_{DD} instantaneously decreases. As shown in FIG. 5, when the DC driving voltage V_{DD} instantaneously decreases and is less than the identification voltage V_{IDEN} , the time at that instant is set (defined) as the start reference time t_0 .

Please refer to FIG. 4B, which shows a circuit diagram of the identification circuit of the LED module according to a second embodiment of the present disclosure. Since substrates of the p-type MOSFET switches S_{21} , S_{22} , S_{23} are connected together as a common reference point (i.e., the substrate is directly used), and the circuit characteristic is similar to the extremely small resistance value, currents flowing through the switches S_{21} , S_{22} , S_{23} are very large (for example, 350 mA), and the similar circuit effect is for each LED module. Based on the principle of high current instantaneous discharge, therefore, the relative voltage waveforms of the LED modules may be regarded as overlapping on the same line at the start reference time t_0 .

In other words, the switch SLED is first turned on, and the DC driving voltage V_{DD} instantaneously increases. Afterward, the switch SLED is turned off so that the DC driving voltage V_{DD} instantaneously decreases and the relative voltage waveforms of the LED modules may overlap on the same line at the start reference time t_0 . Therefore, the start reference time t_0 is used as the reference time of calculating time difference values. At this condition, the switching switch SW is switched from the connection between a second end and a first end to the connection between the second end and a third end, that is, from a path composed of the series-connected switches S_{21} - S_{23} to a path composed of a switch S_{24} . At this time, the time is recorded as the start reference time t_0 , and the start reference time t_0 is used as a reference time of calculating time difference values. Afterward, the switch SLED is turned on and the DC driving voltage V_{DD} slowly increases by for example, but not limited to, connecting to a capacitor component, and therefore the voltage of the LED module gradually increases. When the voltages of the plurality of LED modules gradually increase to reach the identification voltage V_{IDEN} , the plurality of time difference values of the LED modules can be acquired. Take the first LED module as an example, a first time difference is $T_1 = t_1 - t_0$. Therefore, the complete 50 sets of relative voltage waveforms can be shown in FIG. 5.

Please refer to FIG. 4C, which shows a circuit diagram of the identification circuit of the LED module according to a third embodiment of the present disclosure. The major difference between the third embodiment and the second embodiment is that the n-type MOSFET switches S_{31} , S_{32} , S_{33} are used, and substrates of the n-type MOSFET switches S_{31} , S_{32} , S_{33} are connected together as a common reference point. The rest of the operation principles may be similar to the identification circuit of the second embodiment, and the detail description is omitted here for conciseness.

Accordingly, the start reference time t_0 can be defined and recorded, and time difference values T_1-T_{50} of the corresponding LED modules LED_1-LED_{50} can be acquired based on the start reference time t_0 .

In one embodiment, the identification voltage V_{IDEN} is, for example, but not limited to, 1.5 volts or 2 volts. In addition, the voltage (before it instantaneously decreased) at the start reference time t_0 is, for example, but not limited to, 3 volts, since an external supply voltage of 150 volts are averagely shared by 50 LED modules.

Furthermore, by building a lookup table in each of the LED modules LED_1-LED_N , the identification and determination of sequencing the LED modules LED_1-LED_N can be implemented. For example, the circuit designer may build the lookup table in advance according to the sequence of the LED modules LED_1-LED_N according to the size (range) of the time difference values (ranges).

As the following table, an implement of the lookup table is exemplified. Take 50 LED modules LED_1-LED_N as an example to illustrate.

sequence	time difference values/ranges (μs)
#1	6-8
#2	8-10
#3	10-12
#4	12-14
#5	14-16
#6	16-18
...	...
#50	104-106

Therefore, after each LED module LED_1-LED_N operates, all LED modules LED_1-LED_N can be sequenced according to the acquired time difference values corresponding to the sequence in the built-in lookup table. For example, when the time difference value of $12.95 \mu s$ of the LED module is acquired, the LED module is determined to be the fourth LED module according to the built-in lookup table. Similarly, when the time difference value of $17.08 \mu s$ of the LED module is acquired, the LED module is determined to be the sixth LED module according to the built-in lookup table. The rest may be deduced by analogy. Therefore, the sequence of the LED modules can be determined according to the time difference values to achieve an automatic sequencing function.

Incidentally, the above-mentioned time difference values in the lookup table are designed based on the time range, that is, it is not compared with a specific time value. As the example disclosed above, the design of sequence correspondence is, for example, but not limited to, in a time range of 2 microseconds (μs). In fact, the time range in the lookup table may be designed differently according to the number of LED modules, the magnitude of the identification voltage V_{IDEN} , or other circuit parameters.

Accordingly, when the sequence of the LED light string having the LED modules is completed, the sequence mode

is finished, and the operation of the identification circuit 10 is no longer required, and the normal operation mode is performed. That is, the sequence data and the lighting data are transmitted to perform the lighting behavior of the LED modules.

Please refer to FIG. 6A and FIG. 6B, which show circuit diagrams of a parallel sequenced LED light string supplied power by a constant-voltage source and a constant-current source according to a first embodiment of the present disclosure, respectively. Furthermore, please refer to FIG. 7A and FIG. 7B, which show circuit diagrams of a parallel sequenced LED light string supplied power by the constant-voltage source and the constant-current source according to a second embodiment of the present disclosure, respectively.

15 As mentioned above, the manner of sequencing the LED light string composed of series-connected LED modules LED_1-LED_N is the time difference values (ranges) built in the lookup table. In addition, the manner of sequencing the LED light string composed of parallel-connected LED modules 20 is the resistance adjustment or resistance compensation. Therefore, for the LED modules connected in series and in parallel (shown in FIG. 2) or the LED modules connected in parallel and in series (shown in FIG. 3), the series-connected structure is implemented according to FIG. 4A to FIG. 4C 25 and FIG. 5, and the parallel-connected structure is implemented according to FIG. 6A and FIG. 6B, and FIG. 7A and FIG. 7B, described as follows.

As shown in FIG. 6A, the parallel-connected LED modules 11, 12, ..., 1N receive a supply power V_{dc} . In this 30 embodiment, the supply power V_{dc} is a constant-voltage source for providing a voltage source with a constant voltage value. The LED modules 11, 12, ..., 1N respectively get different voltages through the wire resistances R_{L1} , R_{L2} , ..., R_{LN} , R_{L1} , R_{L2} , ..., R_{LN} , and the resistances R_1 , 35 R_2 , ..., R_N of the LED modules 11, 12, ..., 1N from the supply power V_{dc} .

At the time of power-on, since the circuits in each of the LED modules 11, 12, ..., 1N have not been started or operated, each of the LED modules 11, 12, ..., 1N may be 40 equivalent to the corresponding resistances R_1 , R_2 , ..., R_N . For the convenience of description, the wire resistance R_{L1} and the wire resistance R_{L1} may be equivalent to the single-wire wire resistance R_{L1} . Similarly, the wire resistance R_{L2} and the wire resistance R_{L2} may be equivalent to 45 the single-wire wire resistance R_{L2} , ..., and the wire resistance R_{LN} and the wire resistance R_{LN} may be equivalent to the single-wire wire resistance R_{LN} .

After the time of power-on, the supply power V_{dc} supplies power to the LED modules 11, 12, ..., 1N. Due to the 50 voltage difference caused by the current flowing through the wire resistances R_{L1} , R_{L2} , ..., R_{LN} , the voltages generated on the LED modules 11, 12, ..., 1N are different. In this embodiment, the voltage difference caused by the power supply V_{dc} of the constant-voltage source through the wire 55 resistances R_{L1} , R_{L2} , ..., R_{LN} is the voltage drop. Please refer to FIG. 6A, which shows a schematic voltage diagram of the parallel sequenced LED light string according to the first embodiment of the present disclosure. A first voltage V_1 on the first LED module 11 is greater than a second voltage V_2 on the second LED module 12, the second voltage V_2 is greater than a third voltage V_3 on the third LED module 13, and the rest may be deduced by analogy. The voltage generated by the front (up-stream) LED module is greater than the voltage generated by the rear (down-stream) LED 60 module, i.e., $V_1 > V_2 > \dots > V_N$. Accordingly, the LED modules 11, 12, ..., 1N are sequenced according to the different generated voltages V_1 , V_2 , ..., V_N . In the 65

following, the different generated voltages $V_1, V_2, \dots, V_N$ and the sequence principle of the LED modules **11, 12, ..., 1N** are described.

In one embodiment, it can be implemented by means of a built-in corresponding look-up table. For example, the circuit designer may build the look-up table in advance according to the power supply V_{dc} , the number of the LED modules **11, 12, ..., 1N**, the (estimated) wire resistances $R_{L1}, R_{L2}, \dots, R_{LN}$ and the resistances $R_1, R_2, \dots, R_N$ for the different generated voltages $V_1, V_2, \dots, V_N$, thereby sequencing the LED modules **11, 12, ..., 1N**.

In order to increase the accuracy of comparison, determination, and identification between the detected voltage and the voltage ranges of the look-up table, each of the resistances $R_1, R_2, \dots, R_N$ in each of the LED modules **11, 12, ..., 1N** is a controllable resistor with an adjustable resistance. When the LED modules **11, 12, ..., 1N** are sequenced at the time of power-on, the resistance value of each of the controllable resistors (that is, the resistances $R_1, R_2, \dots, R_N$) may be designed to be the minimum value so that the current flowing through each of the resistances $R_1, R_2, \dots, R_N$ is maximized. Therefore, the voltages $V_1, V_2, \dots, V_N$ generated on each of the LED modules **11, 12, ..., 1N** can be maximized, thereby increasing the accuracy of comparison, determination, and identification between the detected voltage and the voltage ranges of the look-up table.

As shown in FIG. 6B, in this embodiment, the supply power I_{dc} is a constant-current source for providing a current source with a constant current value. The LED modules **11, 12, ..., 1N** respectively get different voltages through the wire resistances $R_{L1}, R_{L2}, \dots, R_{LN}, R_{L1}, R_{L2}, \dots, R_{LN}$ and the resistances $R_1, R_2, \dots, R_N$ of the LED modules **11, 12, ..., 1N** from the supply power I_{dc} .

At the time of power-on, since the circuits in each of the LED modules **11, 12, ..., 1N** have not been started or operated, each of the LED modules **11, 12, ..., 1N** may be equivalent to the corresponding resistances $R_1, R_2, \dots, R_N$. For the convenience of description, the wire resistance R_{L1} and the wire resistance $R_{L1'}$ may be equivalent to the single-wire wire resistance R_{L1} . Similarly, the wire resistance R_{L2} and the wire resistance $R_{L2'}$ may be equivalent to the single-wire wire resistance $R_{L2}, \dots$, and the wire resistance R_{LN} and the wire resistance $R_{LN'}$ may be equivalent to the single-wire wire resistance R_{LN} .

After the time of power-on, the supply power I_{dc} supplies power to the LED modules **11, 12, ..., 1N**. Due to the voltage difference caused by the current flowing through the wire resistances $R_{L1}, R_{L2}, \dots, R_{LN}$, the voltages generated on the LED modules **11, 12, ..., 1N** are different. In this embodiment, the voltage difference caused by the power supply I_{dc} of the constant-current source through the wire resistances $R_{L1}, R_{L2}, \dots, R_{LN}$ is the voltage rise.

Please refer to FIG. 3B, which shows a schematic voltage diagram of the parallel sequenced LED light string according to the second embodiment of the present disclosure. A first voltage V_1 on the first LED module **11** is less than a second voltage V_2 on the second LED module **12**, the second voltage V_2 is less than a third voltage V_3 on the third LED module **13**, and the rest may be deduced by analogy. The voltage generated by the front (up-stream) LED module is less than the voltage generated by the rear (down-stream) LED module, i.e., $V_1 < V_2 < \dots < V_N$. Accordingly, the LED modules **11, 12, ..., 1N** are sequenced according to the different generated voltages $V_1, V_2, \dots, V_N$. In the

following, the different generated voltages $V_1, V_2, \dots, V_N$ and the sequence principle of the LED modules **11, 12, ..., 1N** are described.

The major difference between the LED light string shown in FIG. 7A and the LED light string shown in FIG. 6A is that the resistance value of each LED module **11, 12, ..., 1N** in the LED light string of FIG. 2A does not have the controllable characteristics as shown in FIG. 1A. Therefore, in order to achieve the effect of resistance compensation, the LED light string shown in FIG. 2A further includes a compensation unit **20** to replace the controllable adjustment of the resistance in each LED module **11, 12, ..., 1N** as shown in FIG. 1A. In other words, the compensation manner with adjustable resistance (that is, the resistance is controllable) shown in FIG. 1A and FIG. 1B will be implemented by the compensation unit **20**. Therefore, not only simplify the circuit control, but also save the circuit costs. In particular, the compensation unit **20** is an integrated circuit (IC), which has a counting function, or the compensation unit **20** is a circuit self-designed by an analog circuit and a digital circuit, which has a counting function.

Therefore, when the power is turned on for the first time, since the resistances $R_1, R_2, \dots, R_N$ are connected in parallel, the equivalent resistance value is the smallest so the current flowing through is the largest. The magnitude of the first voltage V_1 corresponding to the first sequence (first cycle) of the pulse signal can be acquired.

When the (first time) power-on is finished, the first resistance R_1 is turned off and the impedance of the compensation unit **20** is decreased (i.e., the impedance compensation of the compensation unit **20** is performed) so that the equivalent resistance values after the parallel connection will be the same and the current flowing through may be the same. When the power is turned on again, the magnitude of the second voltage V_2 corresponding to the second sequence (second cycle) of the pulse signal can be acquired.

Similarly, when the (second time) power-on is finished, the first resistance R_1 and the second resistance R_2 are turned off and the impedance of the compensation unit **20** is further decreased so that the equivalent resistance values after the parallel connection will be the same. In other words, when both the first resistance R_1 and the second resistance R_2 are turned off, the impedance of the compensation unit **20** is smaller than the impedance when only the first resistance R_1 is turned off so that the current flowing through may be the same. When the power is turned on again, the magnitude of the second voltage V_3 corresponding to the third sequence (third cycle) of the pulse signal can be acquired. Accordingly, the sequence signal may be used as the basis of the sequence, and the impedance of the compensation unit **20** is adjusted (decreased) to maintain the same current so that the voltage difference between any two LED modules is maintained constant, thereby increasing the accuracy of identifying the detected voltage.

In comparison with the constant-voltage power supply shown in FIG. 7A, the impedance compensation of the constant-current power supply shown in FIG. 7B is to increase the impedance of the compensation unit **20** so that the equivalent resistance values after the parallel connection will increase and the current flowing through is decreased. Accordingly, the sequence signal may be used as the basis of the sequence, and the impedance of the compensation unit **20** is adjusted (increased) to maintain the same current so that the voltage difference between any two LED modules is maintained constant, thereby increasing the accuracy of identifying the detected voltage.

Please refer to FIG. 8, which shows a flowchart of a method of automatically sequencing an LED light string according to the present disclosure, and also refer to FIG. 5. The method includes the following steps of: building a start

11

reference time before the LED modules start to operate (S11). Afterward, generating a plurality of time difference values from the start reference time when a working voltage of each of the LED modules rises to an identification voltage after the LED modules operate (S12). Finally, determining the sequence of the LED modules according to the time difference values to achieve an automatic sequencing function (S13).

Incidentally, the method of automatically sequencing the LED light string provided by the present disclosure may correspond to the operation of the above-mentioned LED light string with the automatic sequencing function. Therefore, the detail description of the method of automatically sequencing the LED light string is omitted here for conciseness.

Accordingly, the LED light string with automatic sequencing function and the method of automatically sequencing the same are provided to determine the sequence of the LED modules by using the built-in lookup table to acquire the relationship between the time difference values and the sequence of the LED modules, thereby simplifying the circuit design and quickly complete the sequence of the LED light string.

Although the present disclosure has been described with reference to the preferred embodiment thereof, it will be understood that the present disclosure is not limited to the details thereof. Various substitutions and modifications have been suggested in the foregoing description, and others will occur to those of ordinary skill in the art. Therefore, all such substitutions and modifications are intended to be embraced within the scope of the present disclosure as defined in the appended claims.

What is claimed is:

1. An LED light string with automatic sequencing function, comprising:

a circuit switch,
a plurality of LED modules, electrically connected to the circuit switch, each LED module comprising:
an identification circuit, connected to a drive voltage source, and
a control unit, configured to generate a control signal to turn on and turn off the circuit switch,
wherein before the LED modules start to operate, the control unit turns off the circuit switch so that a working voltage of each LED module is less than an identification voltage and the identification circuit builds a start reference time,
wherein the control unit turns on the circuit switch so that the working voltage increases to the identification voltage and the identification circuit generates a plurality of time difference values from the start reference time,
wherein the LED modules determine the sequence of the LED modules according to the time difference values to achieve an automatic sequencing function.

2. The LED light string as claimed in claim 1, wherein the time difference values are compared with a plurality of time difference ranges to determine the sequence of the LED modules.

3. The LED light string as claimed in claim 2, wherein the time difference ranges are built in a lookup table.

4. The LED light string as claimed in claim 1, wherein the identification circuit comprises:

a plurality of diodes connected in series,
a switch, connected to the diodes in series to form a series-connected path,

12

a resistor, a first end of the resistor connected to a first end of the series-connected path, and
a switching switch, connected to a second end of the series-connected path and a second end of the resistor, and configured to switch the operation of the diodes and the switch of the series-connected path, or the operation of the resistor.

5. The LED light string as claimed in claim 1, wherein the identification circuit comprises:

a plurality of p-type MOSFET switches connected in series to form a series-connected path,
a p-type MOSFET switch, a first end of the p-type MOSFET switch connected to a first end of the series-connected path, and
a switching switch, connected to a second end of the series-connected path and a second end of the p-type MOSFET switch, and configured to switch the operation of the p-type MOSFET switches of the series-connected path, or the operation of the p-type MOSFET switch.

6. The LED light string as claimed in claim 1, wherein the identification circuit comprises:

a plurality of n-type MOSFET switches connected in series to form a series-connected path,
a n-type MOSFET switch, a first end of the n-type MOSFET switch connected to a first end of the series-connected path, and
a switching switch, connected to a second end of the series-connected path and a second end of the n-type MOSFET switch, and configured to switch the operation of the n-type MOSFET switches of the series-connected path, or the operation of the n-type MOSFET switch.

7. The LED light string as claimed in claim 1, wherein the LED modules are connected in series to form the LED light string.

8. The LED light string as claimed in claim 1, wherein the LED modules are connected in series and in parallel to form the LED light string.

9. The LED light string as claimed in claim 1, wherein the LED modules are connected in parallel and in series to form the LED light string.

10. A method of automatically sequencing an LED light string, the LED light string comprising a plurality of LED modules, the method comprising steps of:

(a) building a start reference time before the LED modules start to operate,
(b) generating a plurality of time difference values from the start reference time when a working voltage of each of the LED modules rises to an identification voltage after the LED modules operate,
(c) determining the sequence of the LED modules according to the time difference values to achieve an automatic sequencing function.

11. The method as claimed in claim 10, wherein the step (a) further comprises a step of:

turning off a circuit switch electrically connected to the LED modules so that the working voltage of each of the LED modules is less than the identification voltage to building the start reference time.

12. The method as claimed in claim 11, wherein the step (b) further comprises a step of:

turning on the circuit switch so that the working voltage rises to the identification voltage.

13. The method as claimed in claim **10**, wherein the time difference values are compared with a plurality of time difference ranges to determine the sequence of the LED modules.

14. The method as claimed in claim **13**, wherein the time difference ranges are built in a lookup table. 5
